J. V. JENKINS & E. J. CREIGHTON.
CONCRETE TRUSS GIRDERS BRIDGE,
APPLICATION FILED AUG. 22, 1913.

1,195,820.

Patented Aug. 22, 1916.

UNITED STATES PATENT OFFICE.

JOHN V. JENKINS AND EDWARD J. CREIGHTON, OF DENVER, COLORADO.

CONCRETE TRUSS GIRDER-BRIDGE.

1,195,820.

Specification of Letters Patent. Patented Aug. 22, 1916.

Application filed August 22, 1913. Serial No. 786,127.

To all whom it may concern:

Be it known that we, JOHN V. JENKINS and EDWARD J. CREIGHTON, citizens of the United States, residing at the city and county 5 of Denver and State of Colorado, have invented certain new and useful Improvements in Concrete Truss Girder-Bridges, of which the following is a specification.

Our invention relates to an improvement 10 in concrete truss girder bridges, and the object is to provide an economic bridge which can be constructed by placing the reinforcing metal in forms and concreted in place, or by placing the reinforcing metal in forms 15 and concreted on the ground and afterward assembled into place.

In the accompanying drawings:—Figure 1 is a fragmentary perspective view of a bridge disclosing the manner in which some 20 of the parts are assembled. Fig. 2, is a transverse vertical sectional view of the bridge showing the section on the one end taken through one of the spans where the pocket is located, while the other side is 25 taken on the span directly in front of one of the pockets.

A, represents one of the girders or spans 30 of the bridge which are preformed and placed upon suitable abutments B. These spans preferably consist of horizontal upper and lower beams 1—1 connected at their ends by vertical posts 2. These beams and posts 2 are composed of reinforcing bars, angles or rods 3, which are bound together 35 by means of bars or wires 4—4 to withstand the stress to which they may be subjected.

Arranged at predetermined intervals between the ends of the span or posts are struts 40 C, which are similarly reinforced by vertically arranged angle-irons and wires (not shown). Extending diagonally between the several struts C and end posts 2 are diagonal struts 5, it being understood that the several reinforced elements are embedded in 45 concrete, thus presenting a reinforced span as disclosed. These struts C are somewhat wider than the end portion of the span and are provided with orifices 6 which are substantially rectangular in shape. The upper 50 surface of this orifice is somewhat inclined inwardly as at 7 while the lower surface 8 is horizontally arranged. Adapted to be received within these oppositely disposed orifices 6 are preformed floor beams 9. These

beams are reinforced in the usual manner, 55 and preferably have their outer ends beveled as at 10 on the upper side thereof in a direction opposite to the upper beveled surface of the orifices 6 of the span in which they are received. Protruding from the beveled 60 surfaces of the beam are the reinforcing bars 11, which are adapted to bend up into the orifices. It will be noted that the space left between the two beveled surfaces of the orifices 6 and the beam forms a substantially 65 V-shaped pocket flaring outwardly toward the outer edge of the span, which when filled with concrete forms a wedge, which by its shape together by its bond with the previously cast concrete effectually prevents any 70 possible separation of the different elements.

The floor slabs 12 are constructed of reinforcing rods and bars 13 and are provided with an opening 14 at their inner edges, the concrete being applied to the reinforcing 75 rods and after the slabs are placed in position, they are connected together at the center of the floor by concrete 14' which is poured between the slabs, so that the slabs are securely fastened together. The adjoining 80 ends of the slabs are similarly connected together. The outer edges of the slabs project over the inclined surfaces of the beam in such a manner that the lower edges of the slabs are partially embedded in the manner 85 disclosed in Fig. 2, thereby completely uniting the spans, the beams and the floor slab at this point.

We claim:

1. A concrete truss bridge comprising preformed reinforced concrete spans, which have orifices formed therethrough at intervals, preformed beams having their outer ends beveled and adapted to be received within said orifices, the upper surfaces of 90 which are beveled in a direction opposite to the beveled surface of the beams, mechanical means projecting outwardly from the beveled ends of the beams and adapted to be received within said orifices, and fillings molded into said orifices and embedding said metallic members, said filling practically forming a V-shaped wedge flaring outwardly 95 from the inner edge of the girder.

2. A concrete truss girder bridge comprising preformed reinforced concrete spans which have orifices formed therethrough at intervals, preformed beams having their 100

outer ends beveled and adapted to be received within said orifices, the upper surfaces of which are beveled in a direction opposite the beveled surfaces of the beams, mechanical means projecting outwardly from the beveled portion of the beams and adapted to be received within said orifices, floor slabs arranged upon said floor beams, said orifices subsequently filled in with concrete thereby embedding the mechanical means and assisting in securing the beams, girders and floor slab together.

In testimony whereof we affix our signatures, in the presence of two witnesses.

JOHN V. JENKINS.
EDWARD J. CREIGHTON.

Witnesses to signature of John V. Jenkins:

ELLA GRUTSCH,
GEORGE H. GALLUP.

Witnesses to signature of Edward J. Creighton:
